SPRING SEAT CONSTRUCTION

Harold J. Holderness and Fred O. Alm, Detroit, Mich., assignors to Ford Motor Company, Dearborn, Mich., a corporation of Delaware

Application February 10, 1953, Serial No. 336,131

2 Claims. (Cl. 155—179)

This invention relates generally to a spring seat construction, and more particularly to a seat frame incorporating means for mounting and supporting thereon flat wire springs of sinuous or corrugated shape.

An object of the present invention is to provide a spring seat construction having a seat frame integrally provided with means for attaching and supporting the free ends of flat sinuously shaped wire springs. The necessity for providing separate brackets, retainers or the like to secure the springs to the frame is thus eliminated, resulting in a simplified and more economically manufactured and assembled seat construction. A further object is to provide a substantially enclosed pocket for receiving the free end of each wire spring and also for receiving and retaining a lubricant so as to provide a permanent self lubricated connection between the springs and the frame. This construction eliminates objectionable noises and squeaks which might otherwise result from the relative rotation occurring between the frame and the end of each spring as the seat is flexed, and insures the retention of the lubricant and continued quiet operation throughout the life of the vehicle. The enclosed lubricant and spring receiving pocket is obtained in the present invention without additional parts or expensive fabrication since portions of the seat frame are used to form the pockets.

Other objects and advantages of the present invention will be made more apparent as this description proceeds, particularly when considered in connection with the accompanying drawings, in which:

Figure 1 is a semidiagrammatic vertical cross sectional view taken through the spring seat construction of the present invention.

Figure 2 is a fragmentary plan view of the construction shown in Figure 1.

Figure 3 is an enlarged plan view, partly broken away, of a portion of the construction shown at the right hand end of Figure 2.

Figure 4 is a cross sectional view taken on the plane indicated by the line 4—4 of Figure 3.

Figure 5 is an enlarged cross sectional view taken on the plane indicated by the line 5—5 of Figure 2.

Referring now to the drawing, and particularly to Figures 1 and 2, there is illustrated a seat frame which may take various forms, but which is shown here as being of sheet metal construction and having front and rear rails 12 and 13 respectively. A plurality of transversely spaced springs 14 extend longitudinally of the vehicle and span the frame, being connected at their opposite ends to the front and rear rails 12 and 13 thereof. Each spring unit 14 is made of steel wire, bent to a sinuous or corrugated shape, so that adjacent loops 16 thereof are substantially parallel to each other and enable the spring to be longitudinally stretched or compressed under load. Adjacent loops 16 of the spring are connected by integral arcuate portions 17.

As best seen in Figure 1, the spring 14 has a crowned seating portion 18 and is formed at its forward end with

2

successive reversely bent portions 19 and 21 forming a conventional "fish mouth" portion.

Referring now to Figure 2, it will be seen that the end loops 16 at the forward end of the spring rest upon the upper surface of the generally box section front rail 12 of the frame, with the extreme forward loops being inserted through apertures 22 formed in the upper wall of the rail and beneath the intermediate raised portion 23 so as to retain the spring against longitudinal displacement relative to the frame. A tab 24 is bent upwardly from the rail 12 and engages the adjacent arcuate connecting portion 17 of the spring to locate the spring in a transverse direction.

At its rearward end, the crowned seating portion 18 of the spring integrally merges into successive reversely bent portions 26 and 27, with the portion 27 being connected to the rear frame rail 13 in the manner to be described more in detail hereinafter.

As best seen in Figures 3, 4 and 5, the rear frame rail 13 comprises a single sheet metal member being generally of box section having front and rear walls 28 and 29 respectively and top and bottom walls 31 and 32 respectively. The bottom wall 32 of the frame rail has a forwardly extending marginal flange 33 projecting outwardly beyond the box section portion of the rail, and the front wall 28 of the rail is bent at right angles to form a similar forwardly projecting marginal flange 34 positioned immediately adjacent the flange 33 of the bottom wall of the rail. The juxtaposed flanges 33 and 34 thus extend generally horizontal and are in contact with each other, being secured together as by spot welding or other suitable means.

The forwardly projecting lower flange 33 is formed with a transversely elongated depressed groove 36 for receiving and retaining the end loop 37 of the wire spring 14. An opening 38 is formed in the lower flange 33 at one end of the elongated groove 36 to permit the insertion therethrough of the end loop 37 of the wire spring, the latter extending beneath the frame rail 13.

The end of the elongated groove 36 adjacent the opening 38 is of semicircular cross section and corresponds in shape and size to the end loop 37 of the wire spring so as to snugly embrace the latter. The end of the elongated groove 36 remote from the opening 38 is enlarged, however, and forms a bulbous chamber 39 providing clearance between the end of the loop 37 of the spring and the adjacent walls of the groove.

The groove 36, including its bulbous end portion 39, opens upwardly and its open upper side is closed by the adjacent upper flange 34 of the frame rail 13. Thus, the upper and lower marginal flanges 34 and 33 respectively of the frame rail are so formed and cooperate with each other as to provide a substantially enclosed elongated chamber for the reception of the end loop 37 of the wire spring and also for the retention of a quantity of a suitable lubricant. During the use of the seat, the crowned seating portion 18, as well as the reversely bent rearward portions 26 and 27 thereof, flex upwardly and downwardly resulting in a limited oscillation of the end loop 37 within the elongated groove 36 in the rear frame rail. In order to provide a quiet construction free from objectionable noises and squeaks, it is necessary to properly lubricate the metal to metal contact between the end loop of the wire spring and frame rail. This is accomplished in an efficient and permanent manner by means of the construction heretofore described, which provides capacity for an amount of lubricant inserted during the manufacture and assembly of the seat. The lubricant is effectively retained in the bulbous portion 39 of the groove 36 and provides proper lubrication of the joint during the life of the seat. Moreover, this is accomplished without necessity of providing separate brackets, fittings, or other

more expensive fabrication, by utilizing flanges of the frame rail which also serve to afford the requisite strength and rigidity to the rail.

Referring particularly to Figures 3 and 5, it will be noted that the close engagement between the end loop 37 of the spring and the groove 36 results in mounting and anchoring the wire spring in a longitudinal direction to the seat frame. The end of the end loop 37 of the wire spring is positioned near the closed end of the groove 36 thus preventing transverse displacement of the wire spring in one direction. Transverse displacement of the wire spring in the opposite direction is controlled by means of a tab 41 punched out of the lower marginal flange 33 of the rail and bent downwardly to engage the adjacent arcuate portion 17 of the wire spring.

Although the rear frame rail is here shown as being of generally box section with a pair of adjacent forwardly projecting marginal flanges, it will be understood that this invention can be applied to various other shapes of sheet metal frame rails as well.

It will be understood that the invention is not to be limited to the exact construction shown and described, but that various changes and modifications may be made without departing from the spirit and scope of the invention, as defined in the appended claims.

What is claimed is:

1. A seat frame for supporting a wire spring of sinusous shape having spaced parallel loops interconnected at opposite ends by arcuate end portions, comprising a sheet metal frame rail of box section with the lower wall of the box section rail extending horizontally and having a marginal flange extending inwardly of the seat frame beyond the confines of the box section, the inner vertical side wall of the box section frame rail being bent inwardly at right angles to form a second horizontally extending marginal flange lying immediately above said first marginal flange and welded thereto, said first and lower marginal flange having a depressed elongated groove formed therein with its open side facing upwardly toward said second marginal flange to form therebetween an elongated substantially closed pocket for receiving the end loop of said wire spring, said elongated pocket extending parallel to the length of said box section frame rail and being spaced inwardly of the box section, said lower marginal flange having an open-

ing formed therethrough at one end of said groove to permit the insertion into the groove of the end loop of said wire spring, the portion of said elongated groove immediately adjacent said opening having a width corresponding in width to the diameter of the end loop of the wire spring to closely embrace the latter and having a height corresponding to the diameter of the end loop of the wire spring plus the thickness of the lower marginal flange to permit the insertion of the end loop into the groove from beneath the lower flange of the box section frame rail, the opposite end of said elongated groove having an enlarged semi-spherical chamber formed in said lower flange, said chamber projecting beneath the level of the elongated portion of the groove and also being enlarged laterally of the elongated groove to provide clearance on all sides of the terminal end portion of the end loop of the wire spring to receive and retain lubricant, said lower marginal flange of the frame rail extending inwardly a distance sufficiently to at least partially overlap the next adjacent loop of the wire spring to form a support therefor, and a tab bent downwardly from said lower marginal flange to engage the arcuate end of the wire spring connecting the end two loops thereof to prevent displacement of the wire spring from said pocket.

2. A frame construction adapted for retaining end members of springs comprising longitudinally spaced members at least one of which has a box cross section with a flange extending outwardly from the box cross section, said flange being formed by the extension of two of the sides of said box cross section, at least one of said side extensions being formed with a spring receiving groove, said groove being closed at one end and open at the other, said closed end being provided with an enlargement adapted to store suitable lubricant for lubricating the movement of said spring in said groove.
